UNITED STATES PATENT OFFICE.

ALBERT JOHN LAMBERT, OF LONDON, ENGLAND, ASSIGNEE OF ONE-HALF TO THE LAMBERT HEATER & ENGINEERING COMPANY LIMITED, OF LONDON, ENGLAND, A BRITISH COMPANY.

LIQUID-HEATING DEVICE.

Application filed May 18, 1927, Serial No. 192,358, and in Great Britain May 2, 1927.

This invention relates to liquid-heating devices and has for its object to provide an improved construction of device of the type comprising shallow rectangular cells through 5 which the liquid is caused to flow, preferably in succession, from the inlet to the outlet of the device; the heat is supplied to the liquid by a flame, for example a gas or oil burner, or by internal electrical resistances, and when 10 a flame is used, those walls of the cells which transmit the heat are preferably corrugated. The other or exposed sides and edges of the cells are flat and are provided with an enamel or other smooth, glossy surface, to impart a 15 tiled appearance to the whole.

The present invention comprises a heater of the type above described, wherein some or all of the individual cells, and/or groups of cells, are secured together by readily detachable connections, such as unions or stub-nipples; the advantage of this construction is that if any cleaning or repair is necessary, and such operations usually affect only one or a few cells, the particular cells can be 25 readily detached for treatment or for replacement with a minimum of trouble and cost.

According to another feature of this invention, a heater as above described has the 30 detachable connections so arranged, for example, the elements of a union are screwed on to its pipes, as to be adjustable in position relatively to the groups of cells, so that the assembly of the complete device is much 35 facilitated.

According to another feature of this invention, a heater as above described, and comprising two or more superposed layers of cells, has each lower layer connected to and 40 supported from the layer above it by readily detachable connections, situated, for example, at each end of the layer.

According to another feature of this invention, the outlet pipe from the heater is 45 connected to its cell by a union which is provided with a lock-nut to co-operate with the union nut in order that an adequately tight joint may be secured whilst providing a swivelling joint, and the parts locked so that the swivelling action does not affect the tightness of the joint.

According to another feature of this invention, a heater as above described comprises end cells, two sets of side cells whereof 55 the cells of each set are permanently connect-

ed together but are detachably connected to the said end cells, and one or more layers of top cells, which layers are detachably connected to the side cells, at least one of said layers having its cells detachable from one 60 another.

This invention also comprises the specific construction of heater hereinafter described and illustrated in the accompanying drawings, in which—

Figure 1 is a perspective view showing the complete device;

Figure 2 is a central sectional view of one end of the group of cells constituting the heater; and

Figure 3 is a plan in section on the line 3—3 of Figure 2.

Like reference characters indicate like parts throughout the drawings.

Referring first to Figure 1, the complete device comprises a cellular structure, indicated generally by the reference numeral 10, which is carried in a trough-like member 11 supported by brackets 12. These brackets also carry adjustable brackets 13 for a gas-burner 14, and arms 15 at the lower end of the brackets 12 are arranged to carry a removable tray which is not shown in the drawing. The liquid is supplied to the cellular structure through an inlet-pipe or stop-cock 16 and the hot liquid is delivered at the open outlet-pipe 17. The pipe 18 communicating with the trough 11 is used to drain off condensation products which may collect therein. As will be seen from this figure, the exposed surfaces of the cells of the structure 10 are rectangular and flat, and they are provided with an enamelled or other suitable surface to simulate the appearance of tiles.

The assemblage of cells 10 is reversible end-for-end in the part 11, and the brackets 13 for the burner 14 are also interchangeable, so that the burner itself can be reversed, thereby facilitating the installation of the heater in that it can suit any arrangement of gas and water supply-pipes.

Referring now to Figures 2 and 3, the detail construction of the cells and the method of securing them together is there illustrated. The end cell 19 has the supply-pipe 16 connected to it by means of a union, one element of the union 20 being secured in the flat wall of the cell 19 by turning over the end 21 against the shoulder provided by the screw-

threaded part which is engaged by the nut 22. Alternatively, the part 20 may be secured by a nut screwed on to its inner end to grip the wall of the cell 19 between it and the enlarged 5 screw-threaded part of the element.

The cells constituting the sides of the structure 10 are preferably permanently connected together to form a set or group, communication between adjacent cells being provided by tubes soldered or otherwise permanently secured to them. The end cell 19 aforesaid communicates with the cell 23 situated at the end of one of the side groups by means of a stub-nipple 24 (see Figure 3), so 10 as to provide a detachable connection. This member comprises a tube with right- and left-hand threads and a non-circular, for example hexagonal, formation at the middle of its length, so that it can be screwed into each of 15 the cells to draw them together; the walls of the cells may be reinforced or thickened in any convenient manner to provide adequate engagement for the threads of the nipple. The cell 19 is connected to the endmost cell 25 20 of the other side group of cells by a similar device 26, but this device does not provide a through passage for the liquid being heated, as it is desired that the liquid should circulate through all the cells. The advantage of 25 using a device which is like a union or nipple but is merely blanked off, is that the liquid has ready access to all parts of it so that it is effectively cooled, and is not damaged or rendered undetachable by the action of the 30 heat on it. Alternatively, the device 26 may be open if it be desired that the liquid should flow through the two side groups of cells in parallel instead of in series.

An end cell opposite to the cell 19 is connected to the two side groups by stub-nipples such as 24, so that a path of circulation is provided from the pipe 16 through the cells 19, 23 and the remainder of that side group to the other end cell, thence by the other side group 45 to the cell 25. From the cell 25 the liquid passes to the end cell of the top layer as shown most clearly in Figure 2.

The inner wall of the cell 25 is provided with a union or bush 27 which may be internally-threaded, which receives an elbow-tube 28, the other end of this tube being upwardly directed and screw-threaded as shown in Figure 2. The externally-coned member 29 of a union is screwed on to the end of a pipe 28 and secured by a lock-nut 30. The co-operating part 31 of the union is similarly secured on the upwardly-extending pipe 32 and secured by a lock-nut 33. The tube 32 is secured, as by soldering, into the lower wall 60 of the end cell 34 of the top layer. The particular arrangement of the parts 29, 31 of the union provides for adjustability in the overall length of the vertical part of the pipes 28 and 32, so that the top layer of cells can be 65 assembled in the correct position with regard

to the side layers. The bush 27 aforesaid also permits of adjustment in a horizontal direction in a similar manner.

The various cells of the top layer are secured together by unions or stub-nipples, as 70 shown at 35, so that the liquid passing from the cell 25 to the cell 34 can circulate along the top-most layer of cells to the further end of the heater-body.

A second lower layer of cells is also provided in the heater; and these are suspended from the top layer. As shown in Figure 2, a union connection is provided between the lower side of a cell of the top layer and the upper side of a cell of the bottom layer. The 75 particular union illustrated in Figure 2 at 36 is blanked off in order that there shall be no passage through it, but the corresponding union at the other end is open to permit the liquid to flow from the top layer to the lower layer. The union is constituted by an internally-coned part which is soldered or otherwise secured to the cell 34, and the co-operating externally-coned part of the union is secured in the upper wall of the cell 37 by nuts 80 38 which lock the union after its effective length has been adjusted as desired.

The use of two unions for supporting the lower layer of cells, whether these unions are open or blanked off, ensures that they will 85 not be damaged by overheating, for the liquid has ready access to their interior and effectively cools them.

The cells of the lower layer may be connected together by stub-nipples similar to 35, but it is preferred to use unions as shown at 39. If desired provision may be made for varying the effective length of these unions in the same way as with the unions 36.

The liquid which is being heated passes 90 from the end cell of the top layer to the cell of the second layer immediately beneath it and thence through all the cells of that layer to the end cell 37 as shown in Figure 2. In some cases yet another layer or layers may be provided, these being secured each to the layer above it in the manner already described, so that the liquid circulates through 95 all of the cells.

The outlet for the heated liquid is arranged 100 as shown in Figure 2, where the outlet-pipe 17 is connected by a union to the cell. The union element 40 is soldered or otherwise secured to the wall of the cell, and the externally-coned part 41 of the union fitting into it is secured by the union nut 42. It is desirable that the pipe 17 should be free to swivel, and the union nut 42 is accordingly screwed up sufficiently to make a tight joint without locking the pipe 17, and the nut 42 is then 105 locked by the lock-nut 43.

In some instances it is more convenient, as for example when a two-way or three-way cock is to be fitted on the outlet pipe, to arrange that the outlet-pipe opens from a cell 110

in the top layer, and in this case the union 29, 31 provides communication from a side-cell to the end cell of the bottom layer; this layer is supported, as before, from the top layer, 5 and the liquid passes from the side-cells, through it, to the top layer.

It will be appreciated that when the liquid circulates through all the cells in succession, its temperature increases during its passage, 10 and if, for example, the heater tends to become furred-up owing to the hardness of the water, it is only those cells where the temperature is highest that become seriously affected, that is to say, in the construction illustrated, the cell 37 and possibly its neighbouring cell. The present construction renders it very easy to remove these cells for cleaning or replacement. This is effected by disconnecting the union 20 and the outlet-pipe 15 20 17. The whole body of cells 10 can then be removed. The union 31 is then undone and the two top layers can be lifted off from the side and end cells, and the lower layer of cells is then exposed. It can then be removed 25 from the top layer by undoing the union 36 and the corresponding union at the other end and then each of the cells of the bottom layer (and also the top layer) is readily accessible and detachable from its companions by means 30 of the unions or nipples connecting them.

Similarly, the end cells are readily detachable from the side groups if it should be required to replace them for any reason, and the whole can be as readily reassembled.

35 If desired the various cells of the side groups can be made detachable from one another, but ordinarily this is not required, and by arranging them closely together the tiled appearance of the whole heater is enhanced.

40 I claim:—

1. A heater comprising groups of interconnected cells forming sides of the heater, a plurality of individual cells arranged in a plurality of layers one above another at the 45 top of the heater, said cells being of shallow rectangular form with flat exterior surfaces and corrugated inner surfaces, detachable connectors for connecting the individual cells and groups of cells and serving to support a lower layer of cells at the top of the heater from the layer of cells above said lower layer, the said detachable connectors for connecting the said layers of cells at the top of the heater and for connecting the said layers to other 50 55 of the cells being also lengthwise adjustable, and said detachable connectors also serving to provide communication in series through the individual cells and groups of cells from one terminal point to another, an inlet connection for the cell at one terminal point, an outlet connection for the cell at one terminal point, an

outlet connection for the cell at the other terminal point, a frame for supporting the cells and a heating element carried by said frame beneath the cells.

2. A heater comprising groups of interconnected cells forming sides of the heater, an individual cell at each end thereof, a plurality of individual cells arranged in a plurality of layers one above another at the top of the heater, said cells being of shallow rectangular 65 70 75 80 85 90 95 100 105 110 115 form with flat exterior surfaces and corrugated inner surfaces, detachable connectors for connecting the individual cells and groups of cells and serving to support a lower layer of cells at the top of the heater from the layer of cells above said lower layer, the said detachable connectors for connecting the said layer of cells at the top of the heater and for connecting the said layers to other of the cells being also lengthwise adjustable, and said detachable connectors also serving to provide communication in series through the individual cells and groups of cells from one terminal point to another, an inlet connection for the cell at one terminal point, an outlet connection for the cell at the other terminal point, a frame for supporting the cells and a heating element carried by said frame beneath the cells.

3. A heater comprising groups of interconnected cells forming sides of the heater, a plurality of individual cells arranged in a plurality of layers one above another at the top of the heater, said cells being of shallow rectangular form with flat exterior surfaces and corrugated inner surfaces, detachable connectors for connecting the individual cells and groups of cells and serving to support a lower layer of cells at the top of the heater from the layer of cells above said lower layer, the said detachable connectors for connecting the said layers of cells at the top of the heater and for connecting the said layers to other of the cells being also lengthwise adjustable, and said detachable connectors also serving to provide communication in series through the individual cells and groups of cells from one terminal point to another, an inlet connection for the cell at one terminal point, an outlet connection for the cell at the other terminal point, said outlet connection comprising a union element on the cell, an outlet pipe, a complementary union element thereon, a union nut for connecting said union elements and a lock nut to cooperate with said union nut, a frame for supporting the cells and a heating element carried by said frame beneath the cells.

In testimony whereof I affix my signature.

ALBERT JOHN LAMBERT.
